SOLVENT REFINING

Louis A. Clarke, Fishkill, N. Y., assignor to The Texas Company, New York, N. Y., a corporation of Delaware

No Drawing. Application March 27, 1937, Serial No. 133,386

5 Claims. (Cl. 196—13)

This invention relates to refining hydrocarbon oil, and more particularly to refining mineral oil by solvent extraction.

The invention contemplates the treatment of hydrocarbon oil to separate the oil into fractions of differing characteristics by extraction with a solvent selected from the group consisting of amino and nitro diphenyl. Amino diphenyl is a compound having the chemical formula:

while nitro diphenyl is a compound having the chemical formula: $\text{NO}_2\text{—C}_6\text{H}_4\text{—C}_6\text{H}_5$.

I have discovered that these compounds, including the ortho, meta and para form of each, are adapted to the extraction of hydrocarbon oil, and particularly mineral oils. These compounds are suitable, for example, for the extraction of motor fuel stock or naphtha for the purpose of separating therefrom fractions rich in constituents having high anti-knock value. They are also suitable for the solvent extraction of lubricating oil for the purpose of separating the oil into fractions respectively rich in paraffinoid and non-paraffinoid constituents. These compounds exert preferential solvent action upon the relatively non-paraffinoid or low viscosity index constituents of the oil, and thus provide a means of refining lubricating oil stock for the production of oil having a relatively high viscosity index.

These compounds are particularly suitable for the extraction of gasoline or naphtha since they have a relatively high boiling point and, therefore, make it possible to separate the solvent from the gasoline or naphtha constituents with facility. As indicated below, these compounds have boiling points of around 300° C. and above at atmospheric pressure, which is substantially above the boiling point of the highest boiling constituents usually present in naphtha or motor fuel stock, the end boiling point of which is around 200 to 250° C.

Boiling point 0° C.

Ortho amino diphenyl	299
Meta amino diphenyl	*254
Para amino diphenyl	302
Ortho nitro diphenyl	320
Para nitro diphenyl	340

*Under 135 mm. pressure.

Accordingly, when extracting motor fuel stock with these compounds, the extraction is made in the usual manner involving either continuous or step countercurrent contact. Separation into extract and raffinate phases results. These

phases are removed and separately subjected to distillation during which the motor fuel constituents, being the more volatile, are distilled from the solvent.

In the case of lubricating oil extraction, where constituents of the oil undergoing treatment may boil at a temperature not greatly different from the boiling temperature of the solvent, separation may be effected by subjecting the mixture of oil and solvent to a washing or displacement treatment, using a liquid medium which, when incorporated in the mixture, renders the oil and solvent substantially immiscible.

The following examples illustrate the application of this invention to the treatment of motor fuel stock for the purpose of separating therefrom a fraction which is rich in constituents having a high anti-knock value. The stock used in these examples comprises a straight run gasoline produced by distillation from East Texas crude. This straight run gasoline had the following tests:

Gravity A. P. I.	54.7
Initial boiling point	°F. 170
Fifty per cent boiling point	°F. 268
End boiling point	°F. 346
Octane number (C. F. R. M.)	53

A sample of this gasoline is subjected to continuous countercurrent contact with ortho nitro diphenyl, using two parts by volume of solvent to one part by volume of gasoline. When the extraction is carried out at around a temperature of 90° F., separation into extract and raffinate phases occurs. The extract phase comprises the relatively high anti-knock constituents of the gasoline dissolved in the main body of the solvent, while the raffinate phase comprises the relatively insoluble portion of the gasoline mixed with a small amount of the solvent.

These phases are removed and separately subjected to distillation for the purpose of stripping therefrom the gasoline constituents.

The extract portion removed from the extract phase will amount to about 25% of the original straight run gasoline and will have an octane number of about 66 to 70 as determined by the Cooperative Fuel Research Method.

Treatment of another sample of this same gasoline with para amino diphenyl, using the same solvent ratio, and at a temperature of 140° F. produces an extract phase which contains an extract comprising 20% of the raw gasoline and also having an octane number of 66 to 70, determined by the same method.

The extractive treatment of the oil with the solvents of my invention may be carried out in either continuous or step countercurrent operation. If desired, the extraction may be carried 5 out in a batch treating operation. Extraction may be effected in a countercurrent tower type of apparatus in which the solvent is introduced near the top of a packed vertical tower, while the oil to be treated is introduced near the bottom of the tower.

While in the foregoing examples, certain solvent ratios and extraction temperatures have been specifically mentioned, it is contemplated that these may be varied, depending upon the 15 nature of the stock undergoing treatment as well as upon the degree of extraction desired.

Obviously, many modifications and variations of the invention, as hereinbefore set forth, may be made without departing from the spirit and scope thereof, and therefore only such limitations should be imposed as are indicated in the appended claims.

I claim:

1. In the refining of hydrocarbon oil to separate the oil into fractions respectively rich in paraffinoid and non-paraffinoid constituents, the method comprising extracting the oil with a solvent selected from the group consisting of nitro and amino diphenyl, forming an extract phase comprising non-paraffinoid constituents dissolved

in the bulk of the solvent and a raffinate phase comprising paraffinoid constituents mixed with a small portion of the solvent, separating the two phases, and removing the solvent therefrom.

2. The method according to claim 1 in which 5 the solvent comprises ortho nitro diphenyl.

3. The method according to claim 1 in which the solvent comprises para amino diphenyl.

4. The method of producing a high anti-knock motor fuel from a motor fuel stock containing 10 constituents of low and high anti-knock value comprising extracting said stock with a solvent selected from the group consisting of nitro and amino diphenyl, forming an extract phase comprising high anti-knock constituents of the stock 15 dissolved in the main body of the solvent and a raffinate phase comprising constituents of low anti-knock value, separating the two phases, and removing the solvent therefrom.

5. The method of solvent refining hydrocarbon 20 oil to separate the oil into fractions respectively rich in paraffinoid and non-paraffinoid constituents comprising extracting the oil with nitro-diphenyl, forming an extract phase comprising non-paraffinoid constituents dissolved in the bulk 25 of the solvent and a raffinate phase comprising paraffinoid constituents mixed with a small proportion of the solvent, and separating the two phases.

LOUIS A. CLARKE. 30
